UNITED STATES PATENT OFFICE

ROBERT SONNTAG, OF JERSEY CITY, NEW JERSEY

CLOTHESLINE PROTECTING DEVICE

Application filed June 17, 1931. Serial No. 545,114.

The present invention relates to new and useful improvements in clotheslines, and more particularly it pertains to a new and novel device for protecting clothes from dirt which may have accumulated upon a clothesline when the same is not in use.

I am aware that such devices have been heretofore devised, but all such devices with which I am familiar have many disadvantages which my invention is designed to eliminate.

It is one of the objects of the invention to provide a new and novel form of device for paying out a protecting element in the form of a tape which is adapted to surround the clothesline and cover the same as the clothes are attached to the line.

It is a further object of the invention so to construct a device of this character that the protecting tape will at all times be smooth and straight for regular laying upon the clothesline.

It is a still further object of the invention so to construct a device of this character that the tape will be paid out or reeled in automatically by manipulation of the clothesline and in a manner entirely independent of the pulleys around which the clothesline passes.

A further object of the invention resides in a novel construction whereby the reel upon which the protecting tape is wound is operated by frictional contact with the clothesline thus insuring a proper paying off and taking up of the tape regardless of the change in diameter of the tape body carried by the tape reel.

Other objects of the invention will become apparent as the nature of the invention is better understood and for this purpose, reference will be had to the accompanying drawing forming a part of this application and in which,

Figure 1 is a view in side elevation partly in section of a device constructed in accordance with the present invention,

Figure 2 is a top plan view thereof, Figure 3 is a vertical sectional view taken on the line 3-3 of Figure 1, and;

Figure 4 is a perspective view of the tape guide, the guide being detached from its frame.

Referring more specifically to the drawing, the reference character 5 designates a clothesline pulley of conventional type which is rotatably mounted in a frame 6 which in turn is mounted for movement in a horizontal plane about a vertical pivot 7. The pivot 7 comprises a bolt, screw or the like 8 mounted in the arms of a suitable bracket 9 which in turn is secured to a window sill 10. The bracket may be supported by walls, posts or any other suitable support in lieu of the window sill 10.

The present invention includes a tape reel 15 and said tape reel 15 is mounted for rotation upon a bolt or the like 16 which has a head 17 and a threaded extremity 18 for the reception of a nut 19. This pivotal mounting of the tape reel 15 is carried by a frame which consists of two members 20 pivotally mounted as at 21 in the frame 6 of the clothesline pulley 5.

The frame 20 of the tape reel includes a pair of downwardly curved members 25 each of which is formed with a vertical extension 26 which in turn are connected by means of a transverse brace 27. The entire tape reel frame 20 and its members 25 are pivotally mounted about the pivot point 21 in order that the tape reel may have swinging movement in a vertical plane to accommodate itself to varying tension upon the clothesline.

The clothesline is designated 30, and as illustrated it passes around the roller 5. The protecting tape is designated 31 and is wound upon the tape reel 15 and is adapted to enclose the clothesline 30 as the clothes are placed thereon, the tape being fed automatically by movement of the clothesline. To effect this automatic feeding of the tape, the clothesline

frictionally engages the tape reel 15 or the tape 31 carried thereby, said clothesline passing between the members 25 of the tape reel frame and outwardly at the forward portion thereof as indicated at Y in Figure 1. In its movement through the members 25, the clothesline rotates the tape reel and effects a feeding of the tape from the wheel, or a winding of the tape thereon depending of course upon the direction of travel of the clothesline.

Thus it will be apparent that as the clothesline is moved, the tape reel will be automatically rotated by reason of frictional contact of the clothesline with the tape on the reel and that also, the tape reel is free to rotate independently of the clothesline pulley 5 which is a great advantage in the device in that increased or decreased diameter of the tape body on the tape reel does not effect the rate of speed of the tape as would be the case where the tape is driven directly from the clothesline pulley 5.

Means is provided to guide the tape and insures its even winding upon the tape reel 15, and this means comprises an arched member 35 pivotally mounted as at 36 in the frame of the tape reel 15, and arched over the tape reel 15 has its free end extended downwardly in the line of the tape as it leaves the tape reel 15. The free end of the guide 35 is formed with an eye 37 through which the tape passes. This guide may be formed from a single piece of wire bent upon itself with its free ends Y-shaped as indicated at 39 to provide for pivotally mounting the same, the eye 37 being preferably of elongated form and formed in the looped end of the two members forming the guide 35.

From the foregoing it will be apparent that the present invention provides a new and novel device of this character and one in which the tape will at all times be smooth and flat, and will be fed at the desired speed to lay it upon the clothesline without distortion of the tape. Furthermore, the invention provides a tape feeding mechanism which is entirely independent of the pulley about which the clothesline travels.

While the invention has been herein disclosed in a preferred form, it is to be understood that the invention is not to be limited to the specific construction herein shown, and that it may be practiced in other forms without departing from the spirit thereof.

Having thus described the invention, what is claimed as new, and what it is desired to secure by Letters Patent of the United States, is;

In a structure of the class described, a frame having a pulley mounted thereon, a second frame in alignment with said first mentioned frame having spaced parallel side members pivoted to the frame of said clothesline pulley, a reel mounted between the spaced

parallel side members of said second named frame, a tape trained about said reel, and a guide extending in superposed relation to the tape trained about said reel and having one end thereof pivoted to the second named frame and having the other end thereof provided with a loop receiving said tape, said guide being positioned between the spaced parallel side members of said second named frame.

In testimony whereof I affix my signature.

ROBERT SONNTAG.
